UNITED STATES PATENT OFFICE.

WILLIAM T. HARRIS, OF LOUISVILLE, KENTUCKY.

APPARATUS FOR RETURNING EXHAUST-STEAM TO STEAM-BOILERS.

SPECIFICATION forming part of Letters Patent No. 677,866, dated July 9, 1901.

Application filed November 30, 1900. Serial No. 38,241. (No model.)

To all whom it may concern:

Be it known that I, WILLIAM T. HARRIS, a citizen of the United States, residing at Louisville, in the county of Jefferson and State of Kentucky, have invented certain new and useful Improvements in Apparatus for Returning Exhaust-Steam to Steam-Boilers, of which the following is a specification.

In steam-engine plants as ordinarily designed the steam after passing through the engine "exhausts" and in most instances passes into the open air, with a consequent large waste of heat and power.

It is the object of my present invention to return this exhaust-steam and its condensation to the boiler, where it may be again converted into live steam, with the result that a much less expenditure of heat, and consequently of fuel, is required than is necessary to produce steam directly from water, the exhaust-steam and its condensation being already, as will be readily understood, at a very high temperature.

An apparatus embodying my said invention will be first fully described and the novel features thereof then pointed out in the claims.

Referring to the accompanying drawings, which are made a part hereof, and on which similar reference characters indicate similar parts, Figure 1 is a side elevation of an apparatus embodying said invention; Fig. 2, a central sectional view thereof; and Fig. 3, a transverse sectional view, on an enlarged scale, as seen when looking in the direction indicated by the arrows from the dotted line 33 in Figs. 1 and 2.

The main shell or body B of this apparatus is connected to that portion of any ordinary or desired steam-boiler which is above the water-line (preferably the steam-dome) by means of a steam-pipe 1, which leads to a steam-chamber 2 in said main shell or body. At the other end it is connected to the boiler at or near the bottom, below the water-line, by means of a hot-water pipe 3. At this end it is also connected to a cold-water supply, as a tank or well, by means of a cold-water pipe 4, as in first starting the apparatus into operation it can better be done with cold water, and a small amount of cold water is also necessary to replenish that lost by leakage, &c. The pipes 3 and 4 lead through a water-valve

body 5 and a nipple 6 to a water-chamber 7 in the main shell or body B. The valve-body 5 is a double structure and contains both a 55 hot-water valve 8 and a cold-water valve 9. Within this body, pointing toward the nipple 6, is a curved nozzle 10, leading from the hot-water valve. This construction controls the direction of the flow of the water which is 60 forced through the nipple 6 and into the chamber 7, the arrangement being such that the flow when both the valves 8 and 9 are open is in the same direction, so that neither interferes with or retards the other. I prefer 65 also to provide a main water-valve 11, by which the flow of both the hot and cold water may be shut off at once from the apparatus. This valve is so arranged as to substantially divide the water-chamber into two portions— 70 the main portion 7, into which the water is first received, and a second portion or chamber 12, within which is the steam-injector nozzle 13. Said nozzle is in line with the combining-tube 14, through which the steam and water are forced to the delivery-nozzle 15, which in turn discharges into the exhaust-vacuum nozzle 16, and this into the main discharge-pipe 17, leading back to the steam-boiler.

A vacuum-chamber 18, formed between an outer shell S and an inner shell or wall w, surrounds the combining-tube 14. Connected to the shell of this vacuum-chamber is an overflow-chamber 19, having a nozzle 85 20. A small pipe 21, having a valve 22, runs from the steam-chamber 2 and terminates in a curved ejector or exhausting nozzle 23 in the chamber 19. The last-mentioned apparatus I have denominated a "teaser." The 90 passage-way in the combining-tube 14 communicates by means of radial perforations p with the exhaust-chamber 18, so that water may be drawn into said chamber from said tube through the vacuum-chamber valve 24, 95 when, as is commonly the case, said valve is free to move and be seated or unseated by pressure as it comes thereon. Said valve, however, may upon occasion be fastened shut by means of the valve-stem 25 and the exhaust-chamber thus closed and rendered inoperative.

The exhaust-steam enters the vacuum-chamber 26 in the casing C through the ex-

haust-steam pipe 27, in which is the valve 28, and is drawn thence by the force of the exhaust created by the passage of steam and water through the delivery-nozzle 15 into the 5 exhaust-vacuum nozzle 16 and thence by way of the pipe 17 back to the boiler. A check-valve 29 (which is kept seated when the apparatus is not in operation by a spring 30) prevents any backflow of water from the 10 boiler to the engine through the exhaust-steam pipe.

A branch 31 from the hot-water pipe 3 may lead to the main discharge-pipe 17, said branch having a suitable valve 32 and terminating in a curved nozzle *n*, arranged to discharge longitudinally of said pipe, as shown.

The operation of said apparatus is as follows: Assuming it to be completely out of operation and the valves all closed, I prefer in putting said apparatus into use to first open the cold-water valve 9. I then open the main water-valve 11. I then open the teaser-valve 22, by means of which a small jet of live steam is permitted to pass from the live-steam chamber 2 to the exhausting-nozzle 23 in the chamber 19 and thence out through the nozzle 20, creating a vacuum in the vacuum-chamber 18, which first raises the valve 24 and then draws a small supply of water from the chamber 12 through the combining-tube 14 and out through the radial perforations therein into said chamber, whence it will presently overflow, showing that the water has begun to move through the apparatus. I then by means of its handle *h* open the main live-steam valve 33, which permits the live steam to pass through the injector-point 13 into the combining-tube 14, which drives the 40 water with great force through said tube and through the delivery-nozzle 15, creating a vacuum in the vacuum-nozzle 16 and in the space behind it and unseating the valve 29. At the same time I open the valve 28 in the 45 exhaust-steam pipe 27, which permits exhaust-steam to be withdrawn with the water and sent with great force through the pipe 17 back into the boiler. At about the same time I open the valve 8, admitting hot water 50 directly from the boiler to the apparatus. I presently close or nearly close the cold-water valve 9, for, as will be readily understood, no very great supply of cold water is necessary where my apparatus is used, it 55 being only necessary to start the operation therewith and then replenish the small amount which is wasted by leaking, &c. It is necessary, however, in order that the apparatus shall work at all, that there shall be 60 a circulation of water, and I therefore draw a supply of hot water directly from the boiler by way of the hot-water pipe 3, as above stated. As soon as the apparatus is at work the teaser-valve 22 is closed and the vacuum-valve 24 will automatically close, and during 65 the regular operation of the apparatus said vacuum-chamber and vacuum-chamber valve

and the overflow-chamber and nozzle, as well as the teaser, are wholly inoperative.

Having thus fully described my said invention, what I claim as new, and desire to secure by Letters Patent, is—

1. The combination, with a steam-boiler and a steam-engine, of an apparatus for returning the exhaust-steam from said engine 75 to said boiler, consisting of an injector one portion whereof is connected to said steam-boiler at a point above the water-line, and another portion whereof is connected to said steam-boiler at a point below the water-line 80 therein and also connected to a cold-water supply, said injector being provided with a vacuum - chamber into which the exhaust-steam from the engine is discharged by means of a suitable pipe, said pipe, an exhaust-vacuum 85 nozzle connected with said chamber, and means for establishing a circulation through the injector, whereby the water and exhaust-steam are driven back into the boiler thereby.

2. The combination, in an injector, of the 90 main shell or body containing a live-steam chamber and a water-chamber, suitable connections with the boiler whereby the steam and the water are admitted to said chambers respectively, an injector-nozzle communicating with said steam-chamber and positioned to discharge into a combining - tube which communicates with said water-chamber, said combining - tube having radial perforations therein, a vacuum-chamber surrounding the 100 shell containing said combining-tube at the point where it contains said radial perforations, a valve in said shell, an overflow-chamber 105 communicating with said vacuum-chamber and having a suitable exhausting-nozzle 110 therein, and a small pipe leading from said nozzle to the live-steam chamber and containing a valve, whereby when said valve is opened and the other valves of the apparatus are in proper position water will be drawn up 115 into said vacuum-chamber by the force created by the steam passing through said pipe and nozzle, substantially as set forth.

3. The combination, in an injector, of the 115 main shell or body containing chambers for water and steam, an injector-nozzle leading out of the steam-chamber therein, a suitable valve therefor, a combining-tube leading out of the water-chamber therein and arranged to receive the discharge from said injector-nozzle, a delivery-nozzle forming a prolongation of said combining - tube and passing through an exhaust-vacuum chamber, a check-valve surrounding said delivery-nozzle and closing the orifice leading from said exhaust-vacuum chamber toward the delivery-point 120 against backflow, an exhaust-vacuum nozzle leading from the space containing the check-valve, a pipe surrounding the mouth of the same and leading thence back to the boiler, 125 and a pipe leading from the engine to said exhaust-vacuum chamber and adapted to conduct the exhaust-steam thereto.

4. The combination, with a steam-boiler

and a steam-engine, of an injector containing a steam-chamber, a water-chamber, and a vacuum-chamber, said steam-chamber being connected with the steam-boiler at a point 5 above the water-line, said water-chamber being connected with the steam-boiler at a point below the water-line, and said vacuum-chamber being connected with the exhaust-pipe of the steam-engine, a combining-tube arranged 10 in said structure and leading from the water-chamber through the vacuum-chamber, and an injector-nozzle arranged in line with said combining-tube and leading from the live-steam chamber, said several pipes and passages being provided with suitable valves, whereby the exhaust-steam is delivered into and mingled with the water and driven back 15 into the boiler under the force of the discharge in said injector-nozzle.

20 5. The combination, with a steam-boiler and a steam-engine, of an injector adapted to return the exhaust-steam and its products to the boiler, said injector containing a live-steam chamber, a water-chamber, and a vacuum-chamber, said live-steam chamber being connected to the boiler above the water-line, said vacuum-chamber being connected 25 to the steam-engine and adapted to receive the exhaust therefrom through a suitable pipe, and said water-chamber being connected both 30 to the steam-boiler below the water-line and also to a source of cold-water supply, the hot-water supply terminating in a curved nozzle, 10, around which the cold water passes on its 35 way to the cold-water chamber said injector being also provided with a combining-tube and delivery-nozzle extending from the water-chamber through the vacuum-chamber, an exhaust-vacuum nozzle surrounding the delivery-nozzle and leading from the vacuum-chamber into which the exhaust-steam is 40 conveyed; a pipe adapted to receive the discharge from said exhaust-vacuum nozzle and which leads thence back to the boiler, and an injector-nozzle leading from the live-steam chamber and arranged to discharge into said combining-tube, substantially as set forth.

45 6. The combination, in an injector, of a main body containing a water-chamber and leading from said live-steam chamber, a combining-tube in line therewith having radial perforations and leading through a surrounding shell and through a vacuum-chamber, with the latter of which the exhaust-steam pipe

from the engine is connected, a priming vacuum-chamber surrounding said shell, a valve-seat in said shell, a loosely-mounted valve thereon, and a teaser composed of a small pipe, valve, and nozzle, leading from the live-steam chamber, whereby water is drawn 60 through radial perforations in said combining-tube into said priming vacuum-chamber and the injector thus primed.

7. The combination, with a steam-boiler and a steam-engine, of an injector whereby 65 the exhaust-steam and its products are conveyed back to the boiler from the engine, a connection between said injector and said boiler at a point above the water-line, a second connection between said injector and said 70 boiler at a point below the water-line whereby hot water is conveyed to said boiler through said injector, said connection being provided with a branch coupled to the return-pipe leading from said injector back to the 75 boiler at a point beyond the nozzle thereof whereby a portion of said hot water is adapted to pass through the injector and a part by way of said branch pipe into said return-pipe beyond or ahead of said injector, substantially as set forth.

8. The combination, with a steam-boiler and a steam-engine, of an injector whereby the exhaust-steam and its products are conveyed back to the boiler from the engine, a 85 connection between said injector and said boiler at a point above the water-line, a second connection between said injector and said boiler at a point below the water-line whereby hot water is conveyed to said boiler through 90 said injector, said connection being provided with a branch coupled to the return-pipe leading from said injector back to the boiler at a point beyond the nozzle thereof said branch being coupled to said pipe by means 95 of a coupling containing a curved nozzle, n, whereby a portion of said hot water may be discharged into said return-pipe and unite with the contents thereof without retarding the flow therein, substantially as set forth.

In witness whereof I have hereunto set my hand and seal, at Indianapolis, Indiana, this 24th day of November, A. D. 1900.

WILLIAM T. HARRIS. [L. S.]
